TRIMMING MACHINE

Francis L. Brandt, Marblehead, Mass., assignor to
United Shoe Machinery Corporation, Borough
of Flemington, N. J., a corporation of New
Jersey

Application July 25, 1939, Serial No. 286,418

18 Claims.

(Cl. 12—47)

This invention relates to apparatus used in the manufacture of shoes and is illustrated herein as embodied in mechanism for trimming the breast portion of a top lift of a wood heel.

It is an object of the present invention to provide apparatus for operating on a work piece and more particularly for effectively trimming off the projecting portion of the top lift of a wood heel flush with the breast face of the heel, although it is to be understood that in its broader aspects the invention is not limited to a machine of the type illustrated herein. A feature of the present invention is the provision of instrumentalities requiring that the shoe be presented to the apparatus in such a manner that the projecting portion of the top lift will be trimmed at the proper angle before the trimming operation can take place.

The apparatus disclosed comprises briefly a trimming block with which cooperates a knife to trim off the breast portion of the top lift of a wood heel which has already been attached to a shoe and gage means for the forepart of the shoe to insure that the heel of the shoe will be at the proper angle with respect to the trimming block so that the projecting portion of the top lift will be trimmed flush with the breast portion of the heel. The trimming block is movable under pressure applied thereto and this movement of the trimming block actuates a single revolution clutch which connects suitable driving mechanism with the trimming knife to cause this knife to move toward and away from the trimming block so as to trim the breast portion of the top lift of the heel presented thereto. The gage means for the forepart of the shoe is suitably connected with latch mechanism which prevents movement of the trimming block under pressure applied thereto through the heel of the shoe, except when the forepart of the shoe is positioned in engagement with the gage means and pressure is applied thereto through the forepart of the shoe. Thus, upon proper presentation of the shoe to the apparatus and the application of a slight pressure to the apparatus by means of the shoe the trimming knife automatically trims the breast portion of the top lift at the proper angle, but this operation of the trimming knife will not take place unless the shoe is presented at the proper angle, which angle is determined by the gage means for the forepart of the shoe. This gage means is made adjustable so that the machine may be used for shoes of varying designs.

Other features of the invention will become apparent upon a study of the specification and

drawings and will be pointed out in the appended claims.

In the drawings,

Fig. 1 is a horizontal sectional view through one form of apparatus embodying the features of this invention and illustrates the manner of presentation of a shoe to the apparatus for the purpose of trimming the breast portion of the top lift of the heel thereof;

Fig. 2 is a sectional view taken on the line II—II of Fig. 1 and illustrates a portion of the mechanism for causing operation of the trimming knife; and

Fig. 3 is a detailed view of the clutch mechanism of Fig. 1 with the clutch parts in engagement.

The frame of the apparatus illustrated includes a base plate 10 by means of which the apparatus may be suitably secured to any supporting structure, the frame also including a forwardly projecting cylindrical wall portion 12 for the reception of the cutting block 14. This cutting block is slidably received by the cylindrical wall portion 12 and includes a reduced central portion 16 with which cooperate the screws 18 threaded into the wall portion 12 for limiting the sliding movement of the cutting block 14. Suitably received by the outer portion of the cutting block 14 is a block 20 of rubber or other suitable material forming a cutting surface with which the trimming knife 22 cooperates. The cutting block may be manually rotated with respect to the cylindrical wall 12 so as to present different portions of its surface to the trimming knife 22 in order to increase the life of the block 20. The inner portion of the cutting block 14 has an extending reduced portion 22 which slides in a corresponding guide way through the wall portion 24 of the apparatus and forms a guide for the cutting block 14. The guide member 22 has its central portion reduced, as at 26, for a purpose to be hereinafter pointed out. The wall portion 24 is also provided with recesses 28 which receive compression springs 30 acting upon the inner surface of the cutting block 14 for biasing the cutting block outwardly, as illustrated in Fig. 2.

The knife 22, which may be flat or curved to conform to the curvature of the breast portion of the heel, is provided with reduced ends 32 (Fig. 2) for reception in slots formed in the outer ends of plungers 34 which are slidable in suitable apertures formed in the cylindrical wall portion 12, this wall portion being increased in thickness at these points to receive the plungers 34. The outer portions of the plungers 34 are threaded for

the reception of nuts 36, each plunger carrying a pair of these nuts between which is clamped the reduced extensions of the knife 22, and by means of which the position of the knife may be adjusted with respect to the cutting block.

The inner portions of the plungers 34 are reduced as at 38 (Fig. 2) and are interconnected by means of a bar 40 which is maintained against the shoulders formed by the reduced portions 38 of the plungers 34. A second bar 42 is also connected to the plungers 34 and is maintained in spaced relationship with respect to the bar 40 by means of spacer sleeves 44 which surround the reduced portions 38 of the plungers 34, the bar 42 being maintained in engagement with the spacer members by means of nuts 46 threaded on the inner portions of the plungers 34, which nuts may be held against rotation by lock washers 48.

Mounted between the bars 40 and 42 is a driving member or collar 50 (Fig. 1) which is rotatably received by a crank member 52, this crank member being formed as an eccentric portion of a shaft 54 suitably journaled in the frame of the apparatus and provided with a flanged portion 56 which bears against the inner wall of the apparatus, as shown in Fig. 1. The collar 50 surrounding the eccentric 52 is also flanged as at 58, its flange being received between the flange 56 and the bars 40 and 42.

Power is supplied to the shaft 54 for driving the same through a clutch mechanism illustrated in detail in Figs. 1 and 3. The outer portion of the shaft 54 is reduced, as at 60, and fixedly associated therewith as by means of a set screw 62 is a collar 64 in which is journaled a cylindrical clutch member 66 having an approximately semi-cylindrical extension as indicated in Fig. 3. To the clutch member 66 is fixed a finger 68 for controlling the position of the clutch member. A spring 70 having one end connected to the arm 68 and the other end connected to the collar 64 biases the clutch member 66 toward the position illustrated in Fig. 3.

Rotatably carried by the reduced portion 60 of the shaft 54 is a constantly driven member 72 which is shown for purposes of illustration as a V-pulley, which may be belted to a suitable driving means, and connected as by a pin 74 is a toothed member 76 which rotates within an enlarged opening formed in the outer end of the collar 64 when the clutch parts are disengaged. However, when the clutch member 66 is moved to the position illustrated in Fig. 3 by means of the spring 70, one of the teeth of the member 66 will move into contact with the flat side of the clutch member 66 and in this manner a driving connection is formed between the constantly driven member 72 and the shaft 54 by means of which a reciprocating motion is imparted to the knife 22 through the eccentric 52 and the collar 50 which acts between the bars 40 and 42. However, if the finger 68 be moved upwardly or in a counterclockwise direction, as viewed in Fig. 3, a sufficient distance to rotate the clutch member 66 through 90°, there will be no portion of this clutch member projecting into the path of the teeth of the member 76 so that this member will then be permitted to rotate with respect to the collar 64 and the shaft 54 will, therefore, be disconnected from the toothed member 76 and may remain at rest.

In order normally to hold the arm 68 in the position wherein the clutch member 66 is out of the path of the teeth of the member 76, a movable stop or abutment member 80 is provided.

This member 80 is generally U-shaped and includes an arm 82 which is normally located in the path of movement of the finger 68, as shown in Fig. 1, so as to hold the finger 68 in its upper position or on the other side of the arm 82 from the position illustrated in Fig. 3. The member 80 has a cylindrical extension 86 slideable in bearings formed in the frame of the apparatus, and a collar 88 is fixed to the cylindrical portion 86 and forms a shoulder against which a compression spring 90 acts, the other end of this compression spring bearing against a bracket 92 secured to the frame of the machine by means of a screw or screws 94. The spring 90 biases the stop member 80 to the left, as viewed in Fig. 1. For holding the stop 80 in the position illustrated when the machine is not operating, a lever 96 is provided, this lever being pivoted to the bracket 92 as at 98 and having at its left end a right angular extension 100 which forms a latch to hold the collar 88 from moving toward the left under the influence of the spring 90. The right end of the lever 96 is received by the reduced portion 26 of the movable guide member 22 which forms the extension of the cutting block 14 so that when the cutting block is in its outermost position, as illustrated in Fig. 1, the left end of the lever 96 is maintained in latching engagement with the collar 88 so as to prevent the stop 80 from moving toward the left under the influence of the spring 90. However, when the cutting block 14 is moved inwardly, the lever 96 is rocked thereby about the pivot 98 in a direction to remove the stop 100 from the path of movement of the collar 88 so that the stop 80 is moved toward the left and the arm 82 moves out of the path of movement of the finger 68 of the clutch member 66. The spring 70 now causes the finger 68 to move downwardly, as viewed in Fig. 3, so that the clutch member 66 will be engaged by one of the teeth of the member 76 to establish a driving connection between the shaft 54 and the driving pulley 72 whereupon the knife 22 is moved toward and away from the cutting block.

In order that the rotation of the shaft terminate after it has completed a single revolution, providing that the pressure on the cutting block 14 has been relieved, the other arm 104 of the movable stop member 80 is provided with an inclined cam surface 106 which lies in the path of movement of a boss 108 connected to the collar 64 so that, as the collar 64 rotates, the boss 108 will move into contact with the cam surface 106 on the arm 104 and will cause movement of this arm to the right which in turn causes the arm 82 to move into the path of movement of the finger 68 of the clutch member 66. As the finger 68 moves into engagement with the arm 82 the finger will be moved upwardly and the clutch member 66 will be rotated out of clutching engagement with the teeth of member 76 against the influence of the biasing spring 70. If pressure has been relieved from the cutting block 14 at this time, it will move outwardly under the influence of the springs 30 and thus cause the left end of the lever 96 to move upwardly as viewed in Fig. 1 whereupon the portion 100 will engage the left side of the collar 88 thus to hold the stop 80 in the position illustrated. In order to insure that the clutch member 66 will move entirely out of engagement with the teeth of the member 76 against the influence of the spring 70, a spring 110 (Fig. 2) is connected to a pin 112 mounted on the bar 40 and a pin 114 mount-

ed on the collar 50, and this spring acts in a direction to move the trimming knife outwardly away from the cutting block to counteract the force of the spring 70 so that the clutch member 66 will not remain partially in engagement with the teeth of member 76 which would tend to cause wear on the teeth and on the clutch member.

Inward movement of the cutting block 14 by pressure on the cutting block alone is prevented by means of a slidable latch member 120 which has a reduced end portion engaging with the reduced portion 26 of the extension 22 of the cutting block 14. When the latch 120 is in the position illustrated in Fig. 1 inward movement of the cutting block is prevented but, upon movement of the latch 120 toward the right, the block 14 may be moved inwardly under the influence of pressure applied thereto, as through the heel of a shoe presented to the cutting surface. The latch 120 is connected by means of a link 124 to an arm 126 of a rocker 128. This rocker 128 is pivoted at 130 between a pair of ears 132 only one of which is illustrated (Fig. 1) and which form a part of a removable cover plate 134 by means of which access may be had to the interior of the machine. The rocker 128 is recessed at 138 to receive a plunger 140 biased outwardly with respect to the rocker by means of a spring 142. The outer end of the plunger 140 rests upon the cover plate 134 of the machine, the spring 142 acting between the plunger and the rocker to bias the rocker 128 in a direction to move the latch 120 into latching engagement with the cutting block.

Adjustably carried by the rocker 128 is a gage member 144 which is positioned to be engaged by the forepart of a shoe when the heel portion is properly presented to the cutting block 14. When pressure is applied through the forepart of the shoe to the gage 144, the rocker 128 moves against the force of the spring 142 so as to release the latch member 120 from the cutting block and thus permit movement of the cutting block inwardly under the influence of pressure applied thereto through the heel of the shoe. In order to limit the movement of the rocker 128 and, accordingly, the movement of the gage 144 with respect to the machine, an adjustable stop 148 is provided, this stop being in the form of a screw threaded through a portion of the rocker 128 and held in adjusted position by means of a lock nut 150.

A felt member comprising portions 160 surrounding the spacer sleeves 44 and having an intermediate portion 162 (Fig. 1) overlying the end of the eccentric portion 52 of the shaft 54 is provided for maintaining the collar 50 and associated parts properly lubricated, the felt 160 surrounding the lower spacer members 44 (Fig. 2) and absorbing oil which may be maintained in the casing below the same.

The operation of the machine will now be briefly reviewed. Upon the proper presentation of a shoe to the machine, as indicated by Fig. 1, the gage member 144 which is engaged by the forepart of a shoe, is moved inwardly under the influence of pressure exerted by the operator on the forepart of the shoe to release the latch 120 from engagement with the extension 22 of the cutting block 14. Pressure applied through the heel of the shoe by the operator will then cause movement of the cutting block 14 inwardly with respect to the frame of the machine whereupon the left end of the lever 96 will be moved out of engagement with the collar 100 connected to the extension 86 of the stop member 80. The spring 90 will now force the stop member 80 toward the left whereupon the arm 82 moves out of registry with the arm 68 of the clutch member 66, and the spring 70 moves this arm in a direction so that the flat side of the clutch member 66 will be moved into the path of movement of the teeth of member 76 and a driving engagement effected between the driving pulley 72 and the shaft 54. The rotation of the shaft 54 will cause the knife 22 to move toward the cutting block 14 whereupon the knife 22 will trim off the breast portion of the top lift of the heel providing that the heel, when presented to the cutting block, has its breast portion in engagement with the side of the knife. As soon as the knife has moved toward the cutting block and has trimmed off the breast portion of the top lift the shoe will be removed by the operator relieving the pressure applied to the cutting block and to the gage 144. As the shaft 54 continues to rotate, the knife 22 will move away from the cutting block and the boss 108, carried by the collar 84 which rotates with the shaft 54, will engage the inclined surface 106 of the stop member 80 to force the stop member toward the right whereupon the arm 82 will move back into the path of movement of the finger 68 and, upon further rotation, the finger will move in a direction to rotate the clutch member 66 out of clutching engagement with the member 76. Since pressure has now been released from the cutting block 14 it will move outwardly which will in turn cause the stop 100 to move into engagement with the collar 88 and hold the stop member 80 in the position illustrated in Fig. 1 until another cycle of operation, as described above, has been initiated.

Should the operator present the shoe to the cutting block and the gage member 144 but fail to bring the breast portion of the heel into engagement with the knife 22, the knife will operate as aforesaid but will not trim the breast portion of the top lift flush with the breast of the heel, but no harm will be done as the operator can repeat the operation with the breast portion of the heel in engagement with the knife. As long as the gage 144 is properly adjusted, under no circumstances will the machine operate to trim the top lift, except in the plane of the breast of the heel or in a plane parallel thereto, should the breast portion of the heel not be brought into contact with the trimming knife. The gage 144 cooperates with the cutting surface 20 of the cutting block 14 to insure that under no circumstances will the machine operate unless the breast face of the heel is at the proper angle with respect to the cutting surface of the cutting block 14. The stop 148 should be adjusted so that the movement of the gage member 144 will be substantially the same as the movement of the cutting block 14 so that the angular relationship between the breast face of the heel and the cutting surface of the block 14 will not change as the gage member and cutting block move under the influence of pressure applied thereto through the shoe by the operator. The gage 144 may be suitably adjusted to adapt the machine to shoes of varying designs.

Having thus described my invention, what I claim as new and desire to secure by Letters Patent of the United States is:

1. In an apparatus for operating on a work piece, a yielding abutment movable from a first position to a second position in response to pres-

sure applied by the presentation of a work piece thereto, means operated by movement of the abutment to the second position for causing an operation to be performed on said work piece, and means acting on said abutment and normally preventing movement of said abutment upon the application of pressure thereto from the first position to the second position but permitting such movement when the work piece is presented to the abutment at a predetermined angular relationship with respect thereto.

2. In an apparatus for operating on a work piece, a yielding work engaging abutment movable from a first position to a second position, means responsive to movement of the abutment to the second position for causing an operation to be performed on the work piece, means normally preventing movement of the abutment from the first position to the second position, and a movable gage member operatively connected to said last-named means and operating to render said last-named means inoperative when said gage is displaced by a portion of said work piece.

3. In an apparatus for operating on a work piece, first movable gage means adapted to be engaged by one portion of a work piece and to be moved from a first position to a second position upon the application of pressure thereto by the work piece, second movable gage means adapted to be engaged by a second portion of said work piece and movable from a first position to a second position under the influence of pressure applied thereto by said work piece, an operating member for operating on said work piece and operative in response to movement of said first gage means to said second position, and means preventing movement of said first gage means to said second position until the second gage means has been moved from its first position to its second position.

4. In an apparatus for trimming the breast edge of the top lift of an attached heel, a cutting block, a trimming knife cooperating with said cutting block, and means actuated by the application of pressure to said cutting block by a heel with the breast portion of the heel in a predetermined angular relationship with respect thereto for causing relative movement between the trimming knife and the cutting block.

5. In an apparatus for trimming the breast edge of the top lift of an attached heel, a trimming member, a positioning device for the heel of a shoe, a positioning device for the forepart of a shoe, and means responsive to the application of pressure to both of said positioning devices for causing the operation of said trimming member.

6. In an apparatus for trimming the top lift of a heel, a cutting block, a trimming knife cooperating with said cutting block for trimming the breast portion of the top lift of a heel presented thereto, means operative upon pressure applied to said cutting block by means of the presentation of a heel thereto for causing relative movement between said cutting block and said trimming knife to perform a trimming operation, and means for preventing said relative movement unless the heel is presented to said trimming block with the breast portion thereof at a predetermined angle with respect thereto.

7. In an apparatus for trimming the breast edge of the top lift of an attached heel, a cutting block movable upon the application of pressure thereto from a first position to a second position, a trimming knife cooperating with said

cutting block, means responsive to movement of said cutting block to said second position for causing operation of said trimming knife, means normally preventing movement of said cutting block to said second position, and gage means adapted to be engaged by the forepart of a shoe when the heel is presented to the cutting block with the breast portion thereof at a predetermined angle with respect thereto and arranged to render said last named means inoperative to prevent movement of the cutting block when so engaged.

8. In an apparatus for trimming the breast edge of the top lift of an attached heel, a cutting block, a trimming knife cooperating therewith to trim the breast edge of the top lift of a heel applied to the cutting block, gage means adapted to be engaged by another portion of the shoe to insure a predetermined angular relationship between the cutting block and the breast portion of the heel, and means operative only upon application of pressure to the cutting block by the heel and application of pressure to the gage means by the other portion of the shoe to cause operation of said trimming knife.

9. In an apparatus for trimming the breast edge of the top lift of an attached heel, a cutting block, a trimming knife cooperating therewith to trim the breast edge of the top lift of a wood heel applied to the cutting block, gage means adapted to be engaged by another portion of the shoe to insure a predetermined angular relationship between the cutting block and the breast portion of the heel, means operative only upon application of pressure to the cutting block by the heel and application of pressure to the gage means by the other portion of the shoe to cause operation of said trimming knife, and means for causing relative adjustment of the positions of said cutting block and said gage means whereby the predetermined angular relationship between the heel of the shoe and the cutting block may be varied.

10. In an apparatus for trimming the breast edge of the top lift of an attached heel, a resiliently mounted cutting block, trimming means cooperating therewith, means responsive to movement of said cutting block under the application of pressure thereto by means of a heel attached to a shoe for causing operation of said trimming means, means normally preventing yielding movement of the cutting block, and yieldable gage means arranged to be engaged by the forepart of a shoe when the heel is properly positioned with respect to the cutting block and arranged to permit movement of said cutting block when moved under the application of pressure thereto by the operator through the forepart of the shoe, the range of movements of the cutting block and the gage means being substantially the same so that the angular relationship between the heel of the shoe and the cutting block will not vary appreciably as pressure is applied to the cutting block and the gage means through the shoe by the operator.

11. In an apparatus for trimming the breast edge of the top lift of a heel, a resiliently mounted cutting block, trimming means cooperating therewith for trimming the breast edge of the top lift of a heel, driving means for causing relative movement between said cutting block and trimming means, a clutch for controlling said movement by said driving means, means responsive to movement of said cutting block under the influence of pressure applied through the heel

thereto by an operator for causing operation of said clutch to initiate a trimming operation, and means normally preventing movement of said cutting block under the application of pressure thereto and arranged to permit such movement only upon the presentation of a heel to the cutting block at a predetermined angular relationship with respect thereto.

12. In an apparatus for trimming the breast edge of the top lift of a heel, a resiliently mounted cutting block, trimming means cooperating therewith for trimming the breast edge of the top lift of a heel, driving means for causing relative movement between said cutting block and trimming means, a clutch for controlling said movement by said driving means, means responsive to movement of said cutting block under the influence of pressure applied through the heel thereto by an operator for causing operation of said clutch to initiate a trimming operation, means normally preventing movement of said cutting block under the application of pressure thereto and adapted to permit such movement only upon the presentation of a heel to the cutting block at a predetermined angular relationship with respect thereto, and means operative upon release of pressure from said cutting block to terminate the trimming operation at a predetermined time.

13. In an apparatus for trimming the breast edge of the top lift of an attached heel, a cutting block movable from a first position to a second position upon the application of a heel thereto, latching mechanism normally preventing such movement, a gage operatively connected to said latching mechanism and adapted to be engaged by the forepart of a shoe for moving the latching mechanism out of latching engagement with said cutting block, trimming means cooperating with said cutting block and operative in response to movement of said cutting block to said second position, and means for causing operation of said apparatus for at least a predetermined length of time after movement of said cutting block to said second position.

14. In an apparatus for trimming the breast edge of the top lift of an attached heel, a movable cutting block, a knife movable toward and away from said cutting block to perform a trimming operation on the top lift of a heel, means

responsive to movement of said cutting block from a first position to a second position by the application of a heel thereto under pressure for causing movement of said trimming knife toward and away from said cutting block, said means comprising a single revolution clutch arranged to terminate the operation of said trimming knife upon the completion of a single cycle of operation thereof, and means engageable and movable by the forepart of a shoe and arranged to prevent movement of said cutting block under the application of pressure thereto except when engaged and moved by the forepart of the shoe.

15. In an apparatus for operating on a work piece, a power operated tool, a plurality of gages for determining the position of a work piece relative to said tool, and means operative only in response to the simultaneous action of pressure by said work piece on all of said gages for operating said tool.

16. In an apparatus for operating on a work piece, a power operated tool, driving means therefor, a clutch for connecting said tool to said driving means, a plurality of gages for determining the position of a work piece relative to said tool, and means operative only in response to the simultaneous application of pressure by said work piece on all of said gages for operating said clutch to connect said tool to said driving means.

17. In an apparatus for operating on a work piece, a reciprocable operating member, a plurality of gages for determining the position of a work piece relative to said operating member, and means operative only in response to the simultaneous application of pressure by said work piece on all of said gages for moving said operating member to and away from the work piece.

18. In an apparatus for operating on a work piece, a reciprocable operating member, driving means therefor, a single revolution clutch for connecting said operating member to said driving means, a plurality of gages for determining the position of a work piece relative to said operating member, and means operative only in response to the simultaneous application of pressure by said work piece on all of said gages for operating said clutch to connect said member to said driving means and cause movement of said member to and away from said work piece.

FRANCIS L. BRANDT.

CERTIFICATE OF CORRECTION.

Patent No. 2,246,664.

June 24, 1941.

FRANCIS L. BRANDT.

It is hereby certified that error appears in the printed specification of the above numbered patent requiring correction as follows: Page 4, second column, line 63, claim 10, for the word "very" read --vary--; page 5, second column, line 43-44, claim 18, for "operaing" read --operating--; and that the said Letters Patent should be read with this correction therein that the same may conform to the record of the case in the Patent Office.

Signed and sealed this 5th day of August, A. D. 1941.

Henry Van Arsdale,

Acting Commissioner of Patents.
